(57) **CLAIM**

The ornamental design for a remote controller for air conditioner, as shown and described.

DESCRIPTION

FIG. 1 is a perspective view of front, right and top side of a remote controller for air conditioner showing our new design; FIG. 2 is a front view thereof; FIG. 3 is a rear view thereof; FIG. 4 is a right side view thereof, a left side view is a mirror image thereof; FIG. 5 is a top view thereof; FIG. 6 is a bottom view thereof; and, FIG. 7 is a reference cross sectional end view of cutting part at 7-7 in FIG. 5 omitting the interior mechanism. The portions of the article in broken lines are shown for illustrative purposes only and form no part of the claimed design.
